UNITED STATES PATENT OFFICE

163,574

BAND SAW OR THE LIKE

Robert L. Crane, Glen Lake, Minn., assignor to
The Doall Company, Des Plaines, Ill., a corpo-
ration of Illinois

Application June 9, 1950, Serial No. 10,434

Term of patent 14 years

(Cl. D93—3)

To all whom it may concern:

Be it known that I, Robert L. Crane, a citizen of the United States, residing at Glen Lake, in the county of Hennepin and State of Minnesota, have invented a new, original, and ornamental Design for a Band Saw or the like, of which the following is a specification, reference being had to the accompanying drawing, forming part thereof.

Figure 1 is an elevational view of the side of a band saw, showing my new design;

Figure 2 is a top view thereof;

Figure 3 is a front view of the band saw; and
Figure 4 is a rear view thereof.

The side opposite that shown in Figure 1 is identical therewith.

The dominant features of my design reside in those portions thereof shown in full lines.

I claim:

The ornamental design for a band saw or the like, as shown and described.

ROBERT L. CRANE.
